UNITED STATES PATENT OFFICE.

ORVILLE D. LA DOW, OF MECHANICSVILLE, NEW YORK, ASSIGNOR OF ONE-HALF TO FREDERICK T. BICKFORD, OF WASHINGTON, DISTRICT OF COLUMBIA.

TELEGRAPH-TRANSMITTER.

SPECIFICATION forming part of Letters Patent No. 416,732, dated December 10, 1889.

Application filed April 2, 1889. Serial No. 305,731. (No model.)

To all whom it may concern:

Be it known that I, ORVILLE D. LA Dow, a citizen of the United States, residing at Mechanicsville, in the county of Saratoga and 5 State of New York, have invented a new and useful Improvement in Telegraph-Transmitters, of which the following is a specification.

My invention relates to telegraph-transmitters, and more particularly to that general 10 class of transmitters in which a single movement of the operator—as, for instance, the depression of a single key or lever—will automatically cause any desired number of variations or impulses of the electric current to 15 be transmitted by means of a suitable conductor to the receiving-instrument and there record or produce the same; and it has for its object to produce a simple, cheap, and effective mechanism, whereby these objects may 20 be attained; and to these ends my invention consists in an apparatus constructed and operating substantially as hereinafter more specifically set forth.

Referring to the accompanying drawings, 25 Figure 1 is a front view of one embodiment of my invention. Fig. 2 is a sectional view thereof. Fig. 3 is a plan view of one key-lever, showing a slightly different arrangement of parts. Fig. 4 is a detail showing one of 30 the sectors of the machine, and Fig. 5 is a diagram showing the preferred construction of the sector.

It is well known that the constant use of the ordinary Morse key by telegraph-operators, in 35 which a greater or less number of movements are necessary to produce each letter, character, or other signal, is not only extremely fatiguing and exhausting work, but that the long-continued practice often produces seri- 40 ous physical results. It has also long been recognized as desirable among those skilled in the art that the operations of transmitting a message by the usual Morse or other code should be simplified, so that the labor and 45 strain upon the operator would be greatly reduced, while at the same time preserving by mechanical means his skill in uniformly and accurately transmitting the respective signals, and many devices have been suggested

for attaining these results. It has further 50 been recognized as a desirable end to be attained to produce an instrument that shall always send the signals in their proper and relative order at the same rate of speed and with mechanical perfection, regardless of the 55 skill of the particular operator sending the same. Furthermore, since it is now common for receiving-operators to utilize the typewriter in recording their transcriptions of 60 telegraphic signals, and since this method has 65 not only greatly lessened the labor of the receiving-operator, but has largely increased his ability to record as well, it is clear that the capacity of the receiving end of a telegraphic circuit is by this means largely in ex- 70 cess of that at the sending or transmitting end, where physical means alone are employed, and hence that the full capacity of such a telegraphic circuit can only be developed by supplanting physical means with 75 mechanical means at the transmitting end also.

My present invention is designed to overcome all these objections and meet these wants, and to furnish a simple, cheap, and effective apparatus that can be used not only to take the place of the ordinary transmitting-key in the hands of the skillful operator and relieve him to a great extent of the strain and labor of sending the proper signals or 80 producing the necessary variations in the electric current to cause said signals to be sent, but can as well be used by the unskilled operator, enabling him to transmit perfect signals and to duplicate the work of those more 85 skilled.

One of the first essentials to such an instrument is to provide means whereby the operator by a single movement will insure the sending of each and every following signal 90 desired at the same rate of speed, regardless of the variations in his work. In order to accomplish this I have arranged a series of keys and key-levers, each one of which is designed to represent some particular character or symbol, which, on being actuated by the operator, shall set in motion automatic mechanism to transmit the particular signal desired; and in 95

order that these varying signals may be properly reproduced I provide a constant force or motor, which, in combination with other devices, shall automatically operate to produce the variations in the current and the impulse or combination of impulses corresponding to the particular key and represented thereby independent of the operator himself.

Referring to the accompanying drawings, in which I have illustrated one simple embodiment of my invention, A represents a suitable frame-work mounted upon supports or standards B and provided with a series of key-levers C, having keys C', which may be arranged in any particular order or style desired, but in the present instance are shown arranged as is usual in the ordinary typewriters, being pivoted at c and held in their normal position by a spring c' and arranged in a series of banks or rows for convenience of fingering, as indicated in the drawings. Connected to each of the key-levers C is a sector D, which in Fig. 2 is shown as pivoted to a strap E, passing around the key-lever and freely suspended therefrom. Mounted upon the frame in suitable cross-bars F G are a series of guide-pins f, extending between the various sectors for the purpose of preventing them interfering with each other in their movements. In place of this arrangement, however, the key-levers may be mortised, as shown in Fig. 3, and the sector D may extend through the mortise and be pivoted therein; and it is evident that other arrangements of the sectors and levers may be made by one skilled in the art which will accomplish substantially the same result. Also mounted in the frame A or suspended from arms projecting therefrom is a non-conducting roller H, which is connected to and driven by some suitable power, as a motor I, which is provided with the usual regulators, so that the roller H will be given a constant and uniform speed in the same direction. This roller may be faced with rubber, cloth, or any other suitable frictional surface which will insure its operation when in engagement with the sectors, as hereinafter described. Also mounted in the frame, or in extensions thereof, is a bar or plate K or a metal comb having an individual tooth or other spring-conductor for each sector, which is arranged to extend in juxtaposition to the roller H and along its periphery, but not in contact therewith, and this bar, plate, or comb K is connected to one of the terminals of the electric circuit by means of a binding-screw k or otherwise. Each of the sectors D is also connected in the electric circuit by any well-known means, either by a separate terminal to each lever or sector, as shown in Fig. 2, or through some portion of the frame common to all of the levers—as, for instance, the fulcrum-point c. The sectors are preferably made of conducting material, and are provided at their segmental surfaces with insulating-blocks d, arranged in proper relations

to each other to leave certain portions of the surface of the sector exposed to correspond to each and every character or signal to be transmitted. Each sector is also provided with another insulating-piece of material, as d', which occupies the same relative position in all of the sectors, and that is preferably a position directly over the roller, comb, or cylinder H.

While it is possible to have the segmental portion of the sector formed of a portion of a single circle, I have found it preferable to give it a form corresponding to segments of two circles having different centers. As, for instance, the portion from 1 to 2 is formed of a segment having the point 3 for a center, while the portion from 1 to 4 is formed of a segment having the point 5 for a center, and the insulating blocks or pieces d' are arranged in the periphery of the sectors at the point of intersection of the two segments, and this point is preferably over the roller H.

It will be seen by reference to Fig. 2 that the sectors are normally held out of contact with the roller, with the insulating-piece d' over the roller, and the sectors may be thus sustained by gravity; or, if preferred, a spring d' may be connected to each sector to normally hold it in position against the bar or plate G, and the face of this plate may be covered with some protecting-surface g to act as a cushion for the sectors. The insulating-piece d' also normally extends over the contact-bar, comb, or plate K, and when the key-lever is depressed the said insulating-piece comes in contact with the roller and conducting plate or comb, and then as the movement of the roller is transmitted to the sector the segmental portion from 1 to 4 is drawn over the conducting-plate at a uniform speed, and the circuit is uniformly opened and closed in accordance with the number of insulating and conducting portions on the sector. In view of the fact that the portion of the sector from 1 to 4 is on a different circle from the portion 1 to 2, the operator is enabled, while still holding one key down during the act of transmitting the signal, to start a succeeding key on its way toward the roller H, for this latter key presents to the roller before absolute contact the portion of the circle from 1 to 2, while the key actually in contact and in operation presents that portion from 1 to 4, or a different circle or arc. This is for the purpose of enabling the operator to closely join or group the several combinations of letters into words. Sometimes, however, I have found it preferable to form the segment of the sector on a single curve having a center at its pivotal point, as represented in Fig. 4.

In order to overcome the necessity of holding the lever throughout the transmission of the full signal, some locking means may be provided that will secure the lever in position until the signal is sent, and I have indicated in Fig. 4 a primitive arrangement

whereby this may be accomplished, and while this has been found to be operative I have other and what I consider better means of accomplishing the same result, which are not 5 specifically described herein. In this case M indicates a bar extending beneath the series of key-levers, and each lever is provided with a pendent pawl N, which will automatically engage with the bar M when the lever 10 is depressed and hold the lever in this position until it is released. In order that this pawl shall be released as soon as the signal is completed, I provide the sector with an extension O, which as soon as the signal is complete 15 shall impinge upon the upper portion of the pawl N and force it from engagement with the rod M and allow the lever to assume its normal position. In this arrangement it is only necessary that the operator shall 20 strike the desired key for an instant and cause it to be depressed, when it becomes locked and remains so until it is automatically released at the conclusion of the signal, and then the next successive key may be struck the same 25 way and the same operation repeated.

From the above description of the construction and arrangement of the parts the operation will be readily understood and need not be specifically set forth in detail, and it will 30 be observed that as the keys are depressed in succession each sector is brought into engagement with the constantly-rotating roller H and with the conducting-bar K, and the roller then propels the sector, so that its periphery 35 passes over the conducting plate or comb and produces the desired signal, with its makes and breaks or variations in the circuit properly spaced and at a uniform speed, which will cause the corresponding record at the receiving-instrument to be accurate and clear, 40 regardless of the technical skill of the transmitting-operator.

Of course the speed with which the signals may be transmitted will depend upon the 45 electrical conditions present and upon the ability of the transmitting-operator to manipulate the keys and the ability of the receiving-operator to understand or interpret the signals and transcribe the same. This 50 speed can be controlled at the will of the transmitting-operator by suitable mechanism to regulate the speed of the roller H.

While I have thus described one embodiment of my invention, it will be evident to those skilled in the art that I am not limited 55 to the precise construction and arrangement of parts shown, as the essential features of my invention may be varied and carried out in many ways without departing from the 60 spirit thereof.

What I claim is—

1. In a telegraph-transmitter, the combination of a non-conducting feed-roller rotating at a uniform rate of speed, a conducting 65 plate or comb arranged adjacent to said roller, a series of sectors having conducting and

non-conducting spaces arranged out of contact with the feed-roller, and a series of key-levers for bringing the sectors into contact with the said roller, substantially as described. 70

2. In a telegraph-transmitter, the combination of a non-conducting feed-roller rotating at a uniform rate of speed, a conducting plate or comb arranged adjacent to said roller, a 75 series of key-levers, and a series of sectors pivotally connected to said levers and arranged to be brought in contact with said non-conducting feed-roller and conducting-plate, substantially as described. 80

3. In a telegraph-transmitter, the combination, with a non-conducting feed-roller rotating at a constant speed, of a conducting plate or comb arranged adjacent to the roller and connected with one terminal of the circuit, a 85 series of key-levers, and a series of sectors pivotally connected to the key-levers arranged out of contact with the feed-roller and connected to the other terminal of the circuit, substantially as described. 90

4. In a telegraph-transmitter, the combination, with a roller rotating at a uniform speed, of a series of levers and a series of sectors connected to said levers, the periphery of each sector being composed of two separate circles, substantially as described. 95

5. In a telegraph-transmitter, a series of sectors, the peripheries of each sector being composed of two separate circles and provided with insulated portions, one portion, as 100 d' , of each sector being arranged in the same relative position to each other upon the part of the periphery corresponding to one circle, and the other portions, as d , arranged in accordance with the various signals to be transmitted upon the part of the periphery corresponding to the other circle, substantially as described. 105

6. In a telegraph-transmitter, the combination, with the roller rotating at a constant 110 rate of speed, of a series of key-levers, a series of sectors connected thereto, and a locking device connected to the levers and released by the sectors, substantially as described. 115

7. In a telegraph-transmitter, the combination, with a roller rotating at a constant rate of speed, of a series of key-levers, a series of sectors connected thereto, and a conducting-plate arranged adjacent to the roller, each 120 sector being provided with an insulating section in its periphery arranged to contact with the conducting-plate when the lever is depressed, substantially as described.

In testimony whereof I have signed my 125 name to this specification in the presence of two subscribing witnesses.

ORVILLE D. LA DOW.
